Primary Examiner — Prabhakar Deshmukh(74) *Attorney, Agent, or Firm* — Banner & Witcoff, Ltd.(57) **CLAIM**

The ornamental design for a handle, as shown and described.

DESCRIPTION

FIG. 1 is a front perspective view of a handle showing my new design;

FIG. 2 is a front view thereof;

FIG. 3 is a rear view thereof;

FIG. 4 is a bottom side view thereof;

FIG. 5 is a top view thereof;

FIG. 6 is a right side view thereof; and,

FIG. 7 is a left side view thereof.

The broken away middle portion of FIGS. 1-5 has been shown to indicate indeterminate length. The broken away portion forms no part of the claimed design. The broken line showing of the interior portion and rear surfaces of the handle is for environmental purposes only and forms no part of the claimed design. The contrast in shading techniques (stippling and line shading) represents a contrast of appearance only and does not represent any particular color, material, texture, or finish.
